CLAIM

The ornamental design for a projector as shown and described.

DESCRIPTION

FIG. 1 is a front, top, right side perspective view of a projector of my design;

FIG. 2 is a rear, bottom, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of area 9 circumscribed in FIG. 1; and,

FIG. 10 is an enlarged view of area 10 circumscribed in FIG. 2.

The broken lines consisting of evenly spaced dash lines in the drawings depict portions of the projector that form no part of the claimed design.

The broken lines consisting of short and long dash lines encircling the enlarged detail views are for annotative purposes that form no part of the claimed design.

1 Claim, 10 Drawing Sheets
